SWITCHES

Elwood T. Platz and Joseph Messing, Detroit, Mich., assignors to Bulldog Electric Products Co., Detroit, Mich., a corporation of West Virginia

Application May 25, 1950, Serial No. 164,098

15 Claims. (Cl. 200—67)

This invention relates to switches in general, and more particularly, discloses a switch characterized by extreme simplicity of design and economy of manufacture while nevertheless preserving high efficiency of operation.

The switch hereof includes an open top box having a swinging cover and containing an insulating base upon which the operating parts of the switch are included. The operating parts include an operating shaft, a handle at one end of the shaft, a contactor at the other end of the shaft and an overcenter spring for overcenter or snap action. The swinging cover mounts a rotary handle which detachably couples to one end of the operating shaft when the cover is moved to a closed position.

A particular object of the present invention resides in the arrangement for establishing an operative connection between the contactor of the switch and the operating shaft.

Another object is the arrangement for mounting the operating shaft of the switch for rotary movement while maintaining a simple construction for those elements. In accomplishing this object the operating metal shaft is journaled in a vertical bore or hole in the base of insulation material and such shaft is formed with a thin or knife edge bearing on the wall of the base bore or hole.

A further object is to provide, in a switch of this general character, a contactor arrangement including a movable plate of insulation material having a movable contact which bridges stationary contacts on opposite sides of the plate whereby the movement of the plate serves as a baffle and as an arc severing means between the stationary contacts.

A further object is to mount the contact carrier, or movable plate of insulation, in such a way that it automatically aligns itself and its movable contacts to the stationary contacts to be bridged or connected by the movable contacts.

Still further objects and aims of the present invention will be better understood upon reference to the appended drawings, illustrating a switch embodying the present invention.

In these drawings:

Fig. 1 is a top plan view of the switch with a cover thereof shown closed and with a handle of the switch shown in the open circuit or "off" position.

Fig. 2 is a top view but with the cover removed and the box open to expose the interior of the switch.

Figs. 3 and 4 are longitudinal sectional views as if on lines 3—3 and 4—4 of Fig. 2 respectively.

Fig. 5 illustrates the switching parts on line 5—5 of Fig. 3, in "off" or open circuit position.

Fig. 6 illustrates the switching parts of Fig. 5 parts in closed circuit or "on" position.

Fig. 7 is a side view along line 7—7 of Fig. 6.

Fig. 8 is a transverse sectional view for line 8—8 of Fig. 3.

Referring to the drawings there is illustrated a switch comprising a box 10 on whose upper edge is hinged, as

2

at 12 and 12, a cover 14 having a central hole 16 journaling the stem portion 18 of a washer 19 secured to a handle 20. To the lower end of the stem portion is secured a U-shaped stirrup or coupler 22 adapted to be detachably coupled, when the cover 14 is swung closed, to certain cooperating parts within the box 10 to be presently described.

Mounted on the bottom 24 of the box 10 by a suitable mounting means such as the clip 26 and a mounting screw 28 is an insulation base 30 having a vertical central hole or bore 32, generally triangular in shape, in which is disposed a vertical operating shaft 33 having an extension or arm 35 projecting laterally into a clear space under a raised portion of the base 30, the clear space affording room for vertical and horizontal movement of the extension 35 at the lower end of the shaft. It is to the upper end of such shaft that the coupler 22 couples the handle 20 when the box cover is swung down and it will thus be seen that horizontal rotary movement of the handle 20, when the cover is closed, will cause similar movement in the same direction of the extension 35 of the operating shaft. Extension 35 is disposed in a slot of an insulation contactor plate or carrier 40 which may be semi-circular in shape and provided with two contactors 42 of U form whose bight passes through openings of the plate 40 and whose opposed legs are on opposite sides of such plate to mate with line contact 44 and load contacts 46 of the base 30 and thus the two contacts 42 may connect the two line and load contacts in pairs, as in a two-pole switch.

Each line contact 44 is on the tip end of a strap 48 attached to the base by a mounting pin or rivet 52 and having a line conductor terminal binding screw 54.

Each load contact 46 is in the form of a thick washer 56 and is secured to the under side of the base 30 by a screw 58 threaded into the contact 46 and which secures to the upper surface of the base 30 a fuse clip 58 adapted to be connected to a similar fuse clip 60 through a cartridge fuse 62. Clip 60 is formed with a strap 64 terminating in a load conductor terminal binding screw 66 under fuse 62. Thus, each pole of the circuit may be completed from the line terminal binding screw 54 to the load terminal binding screw 66 through strap 48, line contact 44, movable contact 42, load contact 46, cartridge fuse clip 58, cartridge fuse 62, cartridge fuse clip 60, and strap 64.

The two poles are suitably separated by barriers 67—68 and 69, projecting upwardly from the base. Barrier 67 buttresses barrier 68 which surrounds the shaft. Barrier 69 forms a marginal wall for a shelf of the base which accommodates a neutral plate 70 fastened to the base by a suitable mounting screw 71 and having suitable neutral conductor binding screws 72, and a neutral plate ground screw 73.

For providing spring bias to hold the parts in assembly and firmly in the base and to provide over center action, there is provided coiled operating spring 74 whose ends are loosely disposed on humped portions 76 and 78 of the extension 35 and on a spring retainer plate 80, respectively. The spring retainer plate 80 is positioned firmly in a vertical slot of the base and tightly engages the mounting screw 28 for the base which threads into the bottom of the box 10. In this way the metal parts are at all times grounded to the box with spring 74 exerting a ground-maintaining bias or pressure on such parts.

The handle 20 and its complementing parts 18, 19 and 22 are grounded to the box through the cover 14 in which they are journaled or mounted.

When the switch cover 14 is swung closed, the handle 20 is coupled through the coupler 22 to the shaft in such a way that lateral rotation of the handle, as indicated in Fig. 1, will cause a similar movement laterally of the contactor plate 40 to move the contacts 42 to and from the

contacts 44—40. The clear areas on the top of the base 30 on which are mounted the cartridge fuse clips 58 are of sufficient size to accommodate cylindrical socket shells, not shown, for receiving plug type fuses. In this way the switch may be provided either with the cartridge fuses and cartridge fuse clips here shown or with plug type fuse socket shells and plug type fuses not shown.

It will also be observed that the operating spring 74 is so positioned that it constantly biases the contactor plate 40 secured to it, upwardly against the under surface of the base 30 at 90, and at the same time longitudinally against a vertical edge 91 of the triangular hole 32 in which the shaft is positioned, and thus provides a spring pressure for the journaled parts against the journalling or bearing surfaces 90—91, these being the vertical edge 91 of the triangular hole 32 in the base 30 and the under surface 90 of the base 30. In this way the spring maintains a most efficient bearing for the operating parts of the switch.

It is to be noted that the operating spring 74 creates a spring pressure contact for security of grounding between the shaft and the screw grounded mounting 28.

We claim:

1. In a switch device, supporting means including a portion having a bore therein, an operating shaft pivotal within said bore and having a radially extending projection, a contact carrier spacing said supporting means and projection and connected to said shaft for pivoting therewith, and an overcenter spring connecting said supporting means and projection and cooperating with the latter for overcenter action, said spring being also biased for yieldingly urging said projection axially against said contact carrier.

2. In a switch device, supporting means including a portion having a bore therein, a pivotal operating shaft within said bore and having a radially extending projection adjacent one end of said bore, said shaft being pivotal within said bore to swing said projection in opposite directions from an intermediate position, a contact carrier pivotally seated at one side against said supporting means adjacent said one end of the bore, said contact carrier being keyed to said shaft to pivot therewith and being seated at the side opposite said one side against said projection to space the latter from said one end of the bore, and an overcenter spring connecting said supporting means and projection and arranged to urge the latter in the direction toward which the projection is swung from said intermediate position.

3. In a switch device, supporting means including a portion having a bore therein, a pivotal operating shaft within said bore and having a radially extending projection adjacent one end of said bore, said shaft being pivotal within said bore to swing said projection in opposite directions from an intermediate position, a contact carrier seated between said projection and supporting means adjacent said one end of the bore and connected with said shaft to pivot therewith, and an overcenter spring connecting said supporting means and projection and arranged when the latter is at said intermediate position to press radially inward on said projection for overcenter action, said spring being also biased to urge said projection axially against said contact carrier.

4. In a switch device, supporting means including a portion having a bore therein, a pivotal operating shaft within said bore and having a radially extending projection adjacent one end of said bore, said shaft being pivotal within said bore to swing said projection in opposite directions from an intermediate position, a contact carrier connected with said shaft to pivot therewith, and an overcenter spring connecting said supporting means and projection to press radially inward thereon for overcenter action when said projection is at said intermediate position.

5. In a switch device, supporting means including a portion having a bore therein, a pivotal shaft having a

radially extending projection, said shaft extending axially from said projection into one end of said bore, a swinging contact carrier mounted on said shaft to float freely axially thereof and being keyed thereto to pivot therewith, said carrier being pivotally seated against said supporting means intermediate the latter and said projection and being also seated against the latter, and overcenter spring means connecting said supporting means and projection and arranged for overcenter action on the latter.

6. In a switch device, supporting means including a portion having a bore therein, a pivotal shaft having a radially extending projection, said shaft extending axially from said projection into one end of said bore and being pivotal therein to swing said projection in opposite directions from an intermediate position, a swinging contact carrier seated between said projection and supporting means adjacent said one end of said bore, said carrier being keyed to said shaft to pivot therewith and being freely floating axially thereof, and overcenter spring means cooperating with said projection for overcenter action thereon, said spring means being also biased for yieldingly urging said projection axially toward said carrier.

7. In a switch device, a housing, an insulation base mounted in said housing, a pivotal shaft having a radially extending projection, said shaft extending axially from said projection into one end of a bore in said base and being pivotal within said bore to swing said projection in opposite directions from an intermediate position, a swinging contact carrier keyed to said shaft for pivoting therewith, a spring retainer, a screw electrically connecting said retainer to said housing, an overcenter spring electrically connecting said retainer and projection and arranged for overcenter action on the latter.

8. In a switching device, supporting means including a portion having a bore therein, said bore having generally opposed sidewall portions converging to an axially extending seat, an operating shaft within said bore and having an axially extending edge pivotally seated against said seat, a contact carrier connected with said shaft for pivoting therewith, and an overcenter spring cooperating with said shaft for overcenter action thereon, said sidewall portions comprising movement limiting stops for pivotal movement of said shaft.

9. In a switching device, supporting means including a portion having a bore therein, said bore having generally opposed sidewall portions converging to an axially extending seat, an operating shaft within said bore and having an axially extending edge pivotally seated against said seat, said shaft also having a radially extending projection, a contact carrier seated between said projection and supporting means and connected with said shaft for pivoting therewith, and an overcenter spring connecting said supporting means and projection and arranged for overcenter action on the latter, said sidewall portions comprising movement limiting stops for pivotal movement of said shaft.

10. In a switch device, supporting means comprising a housing and an insulation base mounted in said housing, said base having generally opposed wall portions converging to an axially extending seat, a swinging operating shaft having an axially extending edge pivotally seated against said seat to swing the shaft toward either of said wall portions from an intermediate position, said shaft also having a radial projection extending in a direction outward from said seat, said wall portions comprising movement limiting stops for said swinging shaft, a contact carrier pivotally seated against said base and spacing the latter from said projection and being also keyed to said shaft to swing therewith.

11. In a switch device, supporting means comprising a housing and an insulation base mounted in said housing, said base having generally opposed wall portions converging to an axially extending seat, a swinging operating shaft having an axially extending edge pivotally seated against said seat to swing the shaft toward either of said

wall portions from an intermediate position, said shaft also having a radial projection extending in a direction outward from said seat, said wall portions comprising movement limiting stops for said swinging shaft, a contact carrier pivotally seated against said base and spacing the latter from said projection and being also keyed to said shaft to swing therewith, and an overcenter spring connecting said supporting means and projection and arranged when the latter is at said intermediate position to press radially inward on said projection for overcenter action, thereby to urge said edge yieldingly against said seat. 10

12. In a switch device, supporting means comprising a housing and an insulation base mounted in said housing, said base having generally opposed wall portions converging to an axially extending seat, a swinging operating shaft having an axially extending edge pivotally seated against said seat to swing the shaft toward either of said wall portions from an intermediate position, said shaft also having a radial projection extending in a direction outward from said seat, said wall portions comprising movement limiting stops for said swinging shaft, a contact carrier pivotally seated against said base and spacing the latter from said projection and being also keyed to said shaft to swing therewith, and an overcenter spring connecting said supporting means and projection and arranged when the latter is at such intermediate position to press radially inward on said projection for overcenter action, thereby to urge said edge yieldingly against said seat, said spring being also biased for yieldingly urging 25 said projection axially against said contact carrier.

13. In a switch device, supporting means including a portion having a bore therein, a swinging shaft having an edge pivotally seated against an axially extending rounded wall portion of said bore to swing said shaft transversely within said bore, a contact carrier connected 30 to said shaft for swinging therewith, and an overcenter spring connecting said supporting means and shaft and arranged for overcenter action on the latter.

to said shaft for swinging therewith, and an overcenter spring connecting said supporting means and shaft and arranged for overcenter action on the latter.

14. In a switch device, supporting means including a portion having a bore therein, a swinging shaft having an edge pivotally seated against an axially extending rounded wall portion of said bore to swing said shaft transversely within said bore, a contact carrier connected to said shaft for swinging therewith, and an overcenter spring connecting said supporting means and shaft and arranged for overcenter action on the latter, said spring being biased for yieldingly urging said pivotally seated edge against said axially extending wall portion of said bore.

15. In a switch device, supporting means including a portion having a bore therein, a swinging shaft having an edge pivotally seated against an axially extending rounded wall portion of said bore to swing said shaft transversely within said bore, said bore having movement limiting wall portions arranged in the path of transverse swinging movement of said shaft, a contact carrier connected to said shaft for swinging therewith, and an overcenter spring connecting said supporting means and shaft and arranged for overcenter action on the latter.
